UNITED STATES PATENT OFFICE.

CHARLES H. BAILEY, OF TROY, NEW YORK, ASSIGNOR TO FULLER & WARREN CO., OF TROY, NEW YORK, A CORPORATION OF NEW YORK.

COMBINATION COAL AND GAS RANGE.

Application filed January 12, 1923. Serial No. 612,212.

To all whom it may concern:

Be it known that I, CHARLES H. BAILEY, a citizen of the United States, residing at Troy, in the county of Rensselaer and State 5 of New York, have invented new and useful Improvements in Combination Coal and Gas Ranges, of which the following is a specification.

Reference may be had to the accompanying drawings, and the reference characters marked thereon, which form a part of this specification. Similar characters refer to similar parts in the several figures therein.

This invention is more particularly adapted for use in connection with a combination coal-and-gas range although it may be used in connection with a coal range.

The invention relates more particularly to the means for furnishing a supply of hot water, and contemplates the use of either the coal fuel in the range or a gas-heater or both for heating the water.

One of the objects of the invention is to obtain more efficient heating action from 25 the gas-heater either as auxiliary to the heat emanating from the coal fuel, or when used alone.

Another object of the invention is to eliminate the possibility of interference of 30 the gas-heater with the combustion of the coal when both sources of heat are employed for heating the water.

Other objects will appear in connection with the following description.

Fig. 1 of the drawings is a view in front elevation of a stove or range embodying my invention.

Fig. 2 is a top plan view of the same partly broken away and partly shown in section.

Fig. 3 is a view in elevation of the rear side of the range partly broken away and partly shown in vertical section.

Fig. 4 is a view of a broken-away portion 45 of the range as shown in Fig. 1, showing the door of the gas combustion chamber open as in the operation of lighting the gas-burner.

Fig. 5 is a vertical longitudinal section

of the range taken on the broken line 5—5 in Fig. 2.

Fig. 6 is a view showing in elevation the inner side of the gas burner.

Fig. 7 is a horizontal section of the range taken on the broken line 7—7 in Fig. 5.

Fig. 8 is a vertical cross-section of the range taken on the broken line 8—8 in Fig. 5.

Fig. 9 is a similar section taken on the broken line 9—9 in Fig. 5.

Referring to the drawings wherein the invention is shown in preferred form, 1 is the body of the stove or range, having the usual fire-box, 2, above the grate, 3, and a smoke-flue, 4.

The outer side wall of the fire-box is formed by the inner side wall, 5, of a water-front comprising a hollow casting to which water is supplied through a pipe, 6, and from which water is delivered through 70 a pipe, 7, said pipes, being connected with suitable openings in the rear end of the water-front.

The water-front is preferably provided with vertical flues, 8.

Adjacent to the outer side wall and lower end wall of the water-front is mounted a gas-burner comprising a hollow casting L-shaped in cross-section as shown in Fig. 5, the horizontal portion, 9, of which burner 80 extends below the water-front and is provided with jet openings, 10, directed toward the bottom of the water-front, as shown in Fig. 5.

The vertical portion, 11, of the burner 85 is provided with jet openings, 12, arranged in vertical rows, as shown in Fig. 6, which rows are directed toward the outer side wall, 14, of the water-front.

Between the neighboring rows of jet 90 openings, 12, the vertical portion, 11, of the burner is provided with vent openings, 13, whereby a plentiful supply of air is delivered adjacent to the jets to facilitate combustion.

The burner is mounted in position by screws, 15, inserted through lugs, 16, into the front end wall, 17, of the range.

Access may be had to the burner to light the same through an opening, 18, in the front wall, 17, of the range, which opening is closed by a door, 19.

5 The front wall, 17, of the range is provided with vent openings, 20, and 21, to insure a sufficient supply of air for the operation of the burner.

10 The space between the water-front and the front end wall, 17, of the range, and through the flues, 8, forms a gas combustion chamber from the rear end of which extends an outlet flue, 22, leading to the smoke flue, 4, a part of the lower wall of which flue is formed by a rearward extension, 23, of the water-front with which the outlet pipe, 7, is connected, whereby the heated water passing from the water-front to the pipe, 7, is subjected to a final heating action due to the passage of the heated products of combustion from the burner, 5, thereover on their way to the smoke flue.

15 The outlet flue, 22, is controlled by a damper, 24, adapted to be operated by means of a crank or handle, 25.

Gas is supplied to the burner by means of a supply-pipe, 26, controlled by a valve, 27, and a gas-and-air mixer, 28.

20 The valve, 27, has an operating member or handle, 29, which can be operated directly by hand or through the medium of an extension rod, 30, extending from the valve-handle, 29, across the front end of the stove

25 and provided with an operating handle, 31, said rod being rotatively mounted in a bearing bracket, 32, on the ash-pit door, 33, as shown in Fig. 1.

30 The gas-valve handle, 29, and the handle or crank, 25, for controlling the damper, 24, are connected together by a link, 34, whereby both are opened in unison and closed in unison.

35 When the range is being operated with coal fuel, the heat from the fire-box, 2, is transmitted to the water-front, causing the same to supply hot water in the usual manner of operating coal ranges.

40 If it be desired to supplement the heat from the coal fuel by heat from the gas-heater, the front door, 19, is opened, the gas is turned on by operating the valve handle, 29, and the gas escaping through the jet openings, 10 and 12, in the burner ignited 45 with a match or in any desired manner. The door, 19, is then closed.

45 The opening of the valve, 29, is accompanied by the opening of the damper, 24, through the medium of the connecting link, 34, as above explained, thus affording a free exit through the outlet flue, 22, for the products of combustion from the gas-heater to the smoke flue, 4. The outlet flue 22, being closed to the fire-box, 2, does not interfere

55 with the combustion of coal fuel in the fire-box in the usual manner.

60 The jets of flame emanating from the jet outlet, 10, in the horizontal portion, 9, of the burner being directed toward the bottom of the water-front cause the bottom of the water-front to be quickly heated, and also cause an upward draft through the flues, 8, of the heated products of combustion which are thus distributed over a wide area of surface of the water-front.

65 The jets of flame issuing from the jet openings, 12, of the vertical portion, 11, of the burner are directed toward the outer side wall of the water-front causing the same to be quickly heated and also cause an upward draft 70 of the heated products of combustion along the outer side of the water-front between the water-front and the end wall, 17, of the range.

75 A baffle-plate, 35, extends between the outer side wall of the water-front and the front end wall, 17, of the range along the upper end of the water-front, causing the products of combustion from the jet openings, 12, to traverse the outer side wall of 80 the water-front before they are permitted to escape at the rear end of said baffle-plate into the flue, 22.

85 The products of combustion passing upward through the flues, 8, enter the space 95 above the water-front, and passing along the top of the water-front escape into the outlet flue, 22.

90 The burner casting is preferably provided with a notch or opening, 36, adjacent to the lower outer corner of the water-front whereby the jets from the openings, 10, may be ignited from the jets from the openings, 12.

95 The space above the water-front is shut off from the fire-box by a plate, 37, which extends from the front end wall, 17, of the range to the upper edge of the water-front as shown in Fig. 5, said plate being for convenience of manufacture made separate from the front end wall, 17, but being in effect a 100 continuation thereof.

105 What I claim as new and desire to secure by Letters Patent is—

110 1. The combination with the body of a stove having a fire-box and a smoke-flue; of a water-front the inner side wall of which forms the front wall of the fire-box; a gas-burner having jet-openings directed toward said water-front, and an outlet flue extending from the space in front of and above said water-front to said smoke-flue and closed to the fire-box.

115 2. The combination with the body of a stove having a fire-box and a smoke-flue; of a water-front the inner side wall of which forms the front wall of the fire-box; a gas-burner having jet-openings directed toward said water-front, an outlet flue extending

from the space in front of and above said water-front to said smoke-flue and closed to the fire-box; and a damper for said outlet-flue.

3. The combination with the body of a stove having a fire-box and a smoke-flue; of a water-front the inner side wall of which forms the front wall of the fire-box; a gas-burner having jet-openings directed toward 10 said water-front, an outlet flue extending from the space in front of and above said water-front to said smoke-flue and closed to the fire-box; a valve controlling the gas-supply to said burner; and connections between 15 said valve and said damper, whereby said gas-supply valve and said damper are opened in unison and closed in unison.

4. The combination with the body of a stove having a fire-box and a smoke-flue; 20 of a water-front the inner side wall of which forms the outer side wall of the fire-box, said water-front being provided with vertical flues therethrough; a gas-burner provided with jet-openings directed toward the 25 bottom of said water-front, and other jet-openings directed toward the outer side wall of said water-front; and an outlet flue leading from the space on the outer side of, and above, said water-front to said smoke-flue, 30 and closed to said fire-box.

5. The combination with the body of a stove having a fire-box and a smoke-flue; of a water-front the inner side wall of which forms the outer side wall of the fire-box, 35 said water-front being provided with vertical flues therethrough; a gas-burner provided with jet-openings directed toward the bottom of said water-front, and other jet-openings directed toward the outer side wall 40 of said water-front; an outlet flue leading from the space on the outer side of, and above, said water-front to said smoke-flue, and closed to said fire-box; and a damper controlling said outlet-flue.

45 6. The combination with the body of a stove having a fire-box and a smoke-flue; of a water-front the inner side wall of which forms the outer side wall of the fire-box, said water-front being provided with vertical flues therethrough; a gas-burner provided with jet-openings directed toward the bottom of said water-front, and other jet-openings directed toward the outer side 50 wall of said water-front; an outlet-flue leading from the space on the outer side of, and above, said water-front to said smoke-flue, and closed to said fire-box; a damper controlling said outlet-flue; a valve controlling the gas-supply to said burner; and connections 55 between said valve and said damper, whereby said gas-supply valve and said damper are opened in unison and closed in unison.

60 7. The combination with the body of a

stove having a fire-box and a smoke-flue; 65 of a water-front the inner side wall of which forms the outer wall of the fire-box, said water-front being provided with vertical flues; a gas-burner comprising a hollow casting L-shaped in cross-section, the horizontal 70 portion of the burner being provided with jet-openings directed toward the bottom of the water-front, and its vertical portion being provided with jet-openings directed toward the outer side wall of the water-front; 75 and an outlet-flue leading from the space at the outer side of, and above, the water-front.

8. The combination with the body of a stove having a fire-box and a smoke-flue; 80 of a water-front the inner side wall of which forms the outer wall of the fire-box, said water-front being provided with vertical flues; a gas-burner comprising a hollow casting L-shaped in cross-section, the horizontal 85 portion of the burner being provided with jet-openings directed toward the bottom of the water-front, and its vertical portion being provided with jet-openings directed toward the outer side wall of the water-front; 90 and an outlet-flue leading from the space at the outer side of, and above, the water-front to said smoke-flue, and closed to the fire-box.

9. The combination with the body of a stove having a fire-box and a smoke-flue; 95 of a water-front the inner side wall of which forms the outer wall of the fire-box, said water-front being provided with vertical flues; a gas-burner comprising a hollow casting L-shaped in cross-section, the horizontal 100 portion of the burner being provided with jet-openings directed toward the bottom of the water-front, and its vertical portion being provided with jet-openings directed toward the outer side wall of the water-front; 105 an outlet-flue leading from the space at the outer side of, and above, the water-front to said smoke-flue, and closed to the fire-box; a damper for controlling said outlet-flue; a 110 valve for controlling the gas-supply to said burner; and connections between said valve and said damper whereby they are opened in unison and closed in unison.

10. The combination with the body of a stove having a fire-box and a smoke-flue; 115 of a water-front the inner side wall of which forms the outer wall of the fire-box, said water-front being provided with vertical flues; and a gas-burner comprising a hollow casting L-shaped in cross-section, the 120 horizontal portion of the burner being provided with jet-openings directed toward the bottom of the water-front, and its vertical portion being provided with jet-openings directed toward the outer side wall of the 125 water-front; and with transverse vent-openings.

11. The combination with the body of a

stove having a front end wall, a fire-box and a smoke-flue; of a water-front the inner side wall of which forms the outer wall of the fire-box, said water-front being provided 5 with vertical flues; a gas-burner provided with jet-openings directed toward the outer side wall of the water-front and with other jet-openings directed toward the bottom of the water-front; a baffle-plate extending 10 across the space from the upper outer edge

of the water-front to the front end wall of the stove; and an outlet-flue leading from the space above the water-front, and from the space beneath said baffle-plate to the smoke-flue.

15

In testimony whereof, I have hereunto set my hand this 20th day of December, 1922.

CHARLES H. BAILEY.
